UNITED STATES PATENT OFFICE

DAVID ROBERT YARNALL, OF PHILADELPHIA, PENNSYLVANIA

CONTINUOUS-SURFACE BLOW-DOWN SYSTEM FOR BOILERS

Application filed March 5, 1920. Serial No. 363,469.

My invention relates to boiler cleaners operating upon the closed circuit skimmer principle for removing sediment from the water handled by means of circulation of the boiler water through a precipitator induced by a temperature differential in the connection from the boiler to the precipitator.

The purpose of my invention is to produce a positive circulation in the skimmer system because of the difference in temperature between the water in the boiler and the water in a precipitator placed below the level of the water in the boiler, wholly independent of boiler inlet feed.

A further purpose is to insert a cooler in the closed skimmer system between the boiler and the precipitator.

A further purpose is to provide circulating means for the skimming system which are capable of regulation or variation in the volume of flow and the flow velocity without regard to the conditions of boiler feed.

Further purposes of my invention will appear in the specification and in the claims.

I have preferred to illustrate one form only, by which the circulation may be secured, among the many means available, selecting a form which is practical, efficient, reliable and inexpensive, and which at the same time well illustrates the principles of my invention.

Figure 1 is a broken side elevation, partly in section, of one form of my invention.

Figure 1^a is a broken side elevation corresponding to Figure 1 but showing a modified form.

Figure 2 is a side elevation, partly in vertical central section, of a gravity precipitator used in a skimmer system.

Figure 3 is a vertical section showing an injector by which the circulation is improved.

In the drawings similar numerals indicate like parts.

Skimmer systems with gravity sediment precipitator have long been operated with circulation induced by the differences in temperature at the inlet and outlet points, and the corresponding difference in weight of equal volumes of water at the two tempera-

tures. These have operated splendidly in some installations and in others the operation has been indifferent and uncertain because of low effective head or for a variety of other possible reasons.

One investigator has proposed to remedy this by causing the boiler feed inlet to induce fluid flow through the precipitator. This is objectionable because it makes the circulation dependent upon the insertion of feed water and restricts the point of insertion of the feed water to the return connection from the precipitator. It injects an outside connection requiring a large liquid volume to make it operate and has a very slow speed.

My invention is intended to make the circulation standard, practically independent of the differences in temperature of the normal precipitator inlet and return connections and free from interference by fluid friction and the other accidental or casual causes of obstruction to flow which affect the less distinct and positive gravity flow, and without the necessity of introducing a pump having moving parts. I use as a fluid inducing means steam from the boiler itself, which has a high temperature and a high inducing velocity but is very low in liquid volume.

I recognize that the character of device by which the flow is increased or standardized may be greatly varied while obtaining substantially the same effect. However, as illustration of all of the possible forms is impracticable as well as unnecessary I have illustrated one distinct type only, in the form of an injector nozzle.

My invention is of course independent of the type of injector used, and could be used with any other suitable means of inducing flow, whether employing steam as a propellant, or utilizing water under pressure or any other suitable energy source.

In Figure 1 I have shown a conventional boiler 10 having hot air pipes 11 and containing a Chase skimmer system illustrated in the application of Lyle G. Chase, Serial No. 254,367, filed September 16, 1918 and in which the longitudinally extending pipe 12 is connected with upwardly extending tubular inlet pipes 13 having wedge-shaped side

openings at 14 alternating in direction, toward the observer and toward the adjacent pipes.

This skimmer system is connected through pipe 15, suitably valved as at 16, with a precipitator 17 of which one form is shown in Figure 2, and through the precipitator by pipes 18, 18', 18² also suitably valved as at 19, with the bottom of the boiler at 20.

For the satisfactory operation of the closed skimming system according to my invention it is necessary that the precipitator be located below the level of the water in the boiler. There is then a downwardly directed flow from the skimmer connection to the precipitator.

The water is cooled between the boiler outlet and the precipitator by a radiator construction illustrated typically at 21 so as to magnify the temperature contrast between the water entering the precipitator and the water in the bottom of the boiler.

The location of the cooler 21 in relation to the level of the water in the boiler is not important. Since the precipitator is located below the boiler water level, the line from the skimmer to the precipitator, and including the cooler, will of course include a vertical leg which will assist the circulation.

The precipitator is shown as having inlet at 22, outlet at 23, and intermediate vertical partition 24 and bell 25, about which sediment settles into the bottom 26. The forms of skimmer system and precipitator are not involved in the present invention, but may both be considered for the purposes of this application as conventional forms.

In order to improve the circulation so as to increase the flow of fluid through the precipitator and give a larger volume of water per unit of time from which the solid matter in suspension may be removed by the precipitator, I apply an accelerator shown in Figure 1 as an injector 27, of which one form is shown in detail in Figure 3. Here steam from the boiler is applied through a suitable nozzle 28, surrounded by water at 29 with the result that water flow is induced downwardly through the pipe 18', causing circulation of the water in the system upon the well known injector principles. The injector should be located above the level of the water in the boiler. Hand valve 30 and check valve 31 are shown for controlling the steam.

The invention is not in the injector itself which for present purposes may be regarded as conventional only. It depends for its success upon the kinetic energy of the steam flow more than offsetting the tendency to reverse flow caused by the heat units absorbed from the steam.

This steam means is capable of easy adjustment to vary the speed of flow by changing the quantity of steam introduced, is simple, is easily applied, affords a minimum of

steam condensation on account of the high temperature of the water handled, and is effective generally to secure any speed and extent of circulation that may prove desirable. It will be noted that it also cooperates to secure a maximum of natural circulation as it increases the contrast of temperature between the water at the precipitator inlet and the return water to the boiler.

The quantity of steam required and speed of circulation best fitted to each individual plant can be determined experimentally by operating at different quantities of steam and speeds of flow over measured times and determining for each the quantity of suspended matter removed from the circulatory system in the precipitator.

In Figure 1^a the structure of Figure 1 is modified to place the injector at about the level of the precipitator outlet.

In Figure 1 I have shown the fluid driving means as located between the precipitator and the bottom of the boiler. However, I wish to clearly indicate that the location of this means is not to be restricted, and that the injector may be located in the closed system on either side of the precipitator or of the cooler, provided the piping is rearranged to place the injector in a position such that it will function properly.

It is my purpose, in view of my disclosure herein, to cover all combinations of driving means, cooling apparatus, and precipitator in a closed skimming system for a steam boiler which may come within the claims or within the spirit and scope of my invention.

Having thus described my invention, what I claim as new and desire to secure by Letters Patent is:—

1. In a steam generating system utilizing a boiler, a skimmer, an artificial cooler, a precipitator, connections through the cooler from the skimmer to the precipitator, upwardly extending return connections from the precipitator from a point below to a point above the level of the water in the boiler, a connection from these return connections extending from the point above the water level in the boiler to the interior of the boiler and a steam jet injector in said last-named connection located at a point above the level of the water in the boiler and adapted to accelerate the speed of the water in the last connection.

2. In a steam generating system utilizing a boiler, a skimmer, a precipitator located below the water level in the boiler, connections extending down from the skimmer to the precipitator, a cooler in the connections, return connections from the precipitator to the boiler and steam circulating means in the return connections located above the level of the water in the boiler.

3. A skimmer system for a boiler, comprising a skimmer adapted to be placed in the

boiler, a precipitator below the water level in the boiler and connections extending down from the skimmer to the precipitator, return connections from the precipitator to the boiler, a cooler in the connections from the skimmer to the precipitator and drive means for positively moving the water in the connections to increase the speed of circulation.
